UNITED STATES PATENT OFFICE.

THOMAS W. JONES, OF BICKNELL, INDIANA.

SAFETY-ELEVATOR.

1,301,791.

Specification of Letters Patent. Patented Apr. 22, 1919.

Application filed November 2, 1918. Serial No. 260,891.

To all whom it may concern:

Be it known that I, THOMAS W. JONES, a citizen of the United States, residing at Bicknell, in the county of Knox and State 5 of Indiana, have invented certain new and useful Improvements in Safety-Elevators; and I do hereby declare the following to be a full, clear, and exact description of the invention, such as will enable others skilled in 10 the art to which it appertains to make and use the same.

This invention relates to safety elevators, and more particularly to means specially adapted for use in connection with elevators 15 or mine cages for preventing dropping of the same in the event of breaking of the lifting cable.

One of the main objects of the invention is to provide a simple and efficient safety device 20 which may be readily applied to an elevator or a mine cage for automatically locking the same against dropping in the event of the lifting cable breaking.

A further object is to provide guide rails 25 for guiding the cage during raising and lowering of the same, the rails being provided with upwardly directed shoulders or teeth and the cage having laterally projecting locking members for engagement with the 30 teeth, these members being normally held in inoperative position by tensioning of the lifting cable.

Another object is to provide a device of the character stated which may be readily applied to a mine cage or elevator of standard construction without necessitating any material changes in the construction of the cage itself.

Further objects will appear from the detailed description.

In the drawings:

Figure 1 is a transverse vertical section through a mine cage with a safety apparatus constructed in accordance with my invention applied, the guide rails and the timbers 45 for supporting the same being shown.

Fig. 2 is a section taken substantially on line 2-2 of Fig. 1.

Fig. 3 is a fragmentary side view showing the plate for guiding and bracing the locking member.

Fig. 4 is a section taken substantially on line 4-4 of Fig. 1.

Fig. 5 is a section taken substantially on line 5-5 of Fig. 1. 55

Fig. 6 is a section taken substantially on line 6-6 of Fig. 1.

Fig. 7 is a detail side view of the plunger.

Fig. 8 is a detail of the blocks for holding the bow springs and the connecting pin 60 therefor.

The cage designated generally by A is of standard and well known construction and is guided during vertical movement in the shaft B between the guide rails 1 which are 65 secured in vertical position within the shaft by means of the securing bolts 2 inserted through the rails and secured to the cross timbers 3 of the shaft. Each of these rails is of channel construction and is provided 70 with an inset central toothed portion 1^a the teeth 4 of which incline upwardly and inwardly of the shaft having their upper faces or shoulders disposed horizontally. The cage is provided at each side, and adjacent 75 the upper and lower ends thereof, with angle plates 5 which are rigidly secured to the sides of the cage, these plates fitting snugly about the lateral faces of the rails so as to guide the cage during raising and lowering 80 of the same. The rails are preferably constructed of suitable lengths of steel so as to have the requisite strength to withstand the strain to which they are subjected, these lengths being bolted together and connected 85 by any suitable or preferred means. It will be understood, of course, that the lengths of the rail sections may be varied as desired.

Substantially rectangular bracing and guide plates 6 are secured to each side of 90 the cage a short distance from the top thereof, these plates being provided with rectangular openings which are in register with similar openings extending through the side walls of the cage. Locking members 7 are 95 slidable through the openings of the plates 6, the outer ends of each of these members being beveled or inclined similarly to the inclination of the teeth 4 so that the lower edge portion of this member extends inwardly above the horizontal shoulder of the tooth when the locking member is in opera- 100

tive position. Member 7 is provided, in its inner portion, with a vertical slot 8 which snugly receives the lower end portion of the outer arm 9 of a bell crank lever 10 which 5 is rockably mounted at its angle in a U hanger 11 depending from the top 12 of the cage and rigidly secured thereto by riveting or in any other suitable manner. The inner end portion of the inner arm 13 of bell crank 10 is provided with a longitudinally extending slot 14 which receives a connecting pin 15. This pin fits snugly through an aperture provided through the lower end portion of a vertically disposed plunger 16 slid- 15 able through top 12 of the cage, the arms of the bell cranks being positioned at opposite sides of this plunger. The body portion 16^a of the plunger is of polygonal cross section and fits snugly through the opening 20 provided through the top of the cage there- for so as to be held against rotary movement while being free from vertical movement. The locking members 7 are thus connected to the plunger 16 so as to be moved inwardly 25 or into inoperative position when the plunger is raised, these members being extended into the path of the teeth 4 of the guide rails 1, when this plunger is depressed.

The ends of the connecting pin 15 are 30 secured in oppositely directed clamping blocks 17 each of which is positioned closely adjacent the inner arm 13 of one of the bell cranks 10. Each of these blocks is provided, in its outer end portion, with a horizontally disposed slot which receives an upwardly directed bow spring 18 of laminated construction, this spring being held in proper position within the block by a securing screw 19, as shown. These two springs are posi- 35 tioned at opposite sides of the plunger 16 and equidistant therefrom, the upper ends of the arms of the springs bearing against the top of the cage, and these springs acting to normally depress the plunger so as 40 to hold the locking members in extended or operative position.

An inverted U-shaped retaining frame 20 is secured to the top 12 of the cage in alignment with the plunger 16, the top bar 21 of 50 this frame being provided with an opening which snugly receives the reduced upper cylindrical portion 22 of the plunger so as to guide the same during vertical movement. Downward movement of the plunger 55 through the top of the cage is positively limited by a stop pin 23 inserted there- through adjacent the upper end of the body 16^a of the plunger. A washer 24 is mounted about the reduced upper portion 22 of the 60 plunger and is held in position thereon by the pin 23 and the shoulders formed at the upper end of the body 16^a. An expansion coil spring 25 is mounted about the reduced upper portion of the plunger and confined 65 between the top bar 21 of frame 20 and the

washer 24, this spring coacting with the bow springs to force the plunger downwardly. Lifting chains 26 are secured at their lower ends to the cage at the top and adjacent each side thereof, the upper ends of these 70 springs being secured through a ring 27 se- cured to the lower end of the lifting cable 28. The upper end of plunger 16 is con- nected by a flexible connection consisting of a plurality of links 29 to the ring 27 so that 75 when the lifting cable is tensioned for rais- ing the cage, the plunger will be moved up- wardly against the downward pressure of the bow springs 18 and expansion spring 25 so as to move the locking members 7 in- 80 wardly into inoperative position. When the plunger is in raised position, the locking members are moved out of the path of the teeth 4 of guide rails 1, but project into the channels of these rails a short distance so 85 as to be readily movable into engagement with the teeth when released. In the event of the cable 28 breaking, or of this cable be- coming slack due to the hoisting mechanism becoming out of order, dropping of the cage 90 will be prevented by the locking members which will be moved outwardly immediately upon release of the plunger so as to engage the teeth of the guide rails thus positively locking the cage in the shaft so as to pre- 95 vent downward movement thereof. As stated, the guide rails are preferably con- structed of suitable lengths of steel so as to be very strong and well able to withstand the strain to which they are subjected. 100

It will be evident that there may be slight changes made in the construction and ar- 105 rangement of the details of my invention without departing from the field and scope of the same, and I intend to include all such variations, as fall within the scope of the appended claim, in this application in which a preferred form only of my invention is disclosed.

What I claim is:

The combination with spaced guide rails provided with upwardly and inwardly in- 110 clined teeth, of a cage slidable between said rails, a lifting cable secured to said cage for raising and lowering the same, bell crank 115 levers rockably mounted within the cage, locking members projecting through the side walls of said cage and connected to the outer arms of the bell crank levers so as to be moved outwardly into position for en- 120 gagement with the teeth of the rails when the inner arms of the bell cranks are de- pressed, a plunger slidable through the top of the cage and connected at its upper end to said cable so as to be raised thereby when 125 the cable is tensioned, a connecting pin in- serted through said plunger adjacent the lower end thereof, blocks secured on the ends of the pin at opposite sides of and equidis- 130 tant from the plunger, and bow spring car-

ried by said blocks and pressing against the top of the cage so as to force the plunger downwardly, said connecting pin being inserted through the inner ends of the inner 5 arms of the bell crank levers and said arms being longitudinally slotted to receive said pin.

In testimony whereof I affix my signature in presence of two witnesses.

THOMAS W. JONES.

Witnesses:

WILL H. MENKE,
JAMES A. JONES.
